poration of OhioNo Drawing. Application May 28, 1948,
Serial No. 29,947

23 Claims. (Cl. 196—52)

1

This invention relates to the conversion of hydrocarbons and is particularly directed to cracking of hydrocarbons in the presence of a small amount of a promoter which decomposes rapidly under the cracking conditions. More specifically, the invention relates to the employment of certain classes of organic peroxides thermally and shock stable at ordinary temperatures but sufficiently unstable at elevated temperatures to decompose rapidly. By incorporation of such materials with a hydrocarbon in a reaction zone, accelerated and improved cracking of the hydrocarbon can be induced.

One of the objects of the invention is to provide a method for converting high-boiling hydrocarbons into low-boiling hydrocarbons, which method brings about improved operation in that it makes feasible the employment of lower temperatures than otherwise useable and results in the production of higher yields than obtained without the promoter.

Another object of the invention is to conduct hydrocarbon conversion operations under conditions which accelerate the rate of reaction, particularly thermal cracking operations.

Other objects and advantages of the invention will in part be obvious and in part appear hereinafter.

The invention, accordingly, comprises the process of cracking hydrocarbons employing certain types of organic peroxides as promoters, which includes the steps and combination of steps having the relationship each to the other to be hereinafter described, in which process the hydrocarbons to be converted are subjected to cracking conditions of time, temperature and pressure in admixture with a small amount of an organic peroxide. The peroxide is preferably injected directly into the reaction zone, either as the pure compound or as a solution in an organic solvent. In cases involving the cracking of hydrocarbon liquids, the peroxide can be added in solution or suspension in a portion of the hydrocarbon liquid itself. When handling the peroxide promoter, it is important that prior to entry into the reaction zone, it should not be subjected to temperatures which would induce decomposition thereof.

Although the specific mechanisms involved in the pyrolysis of peroxides under various elevated temperatures have not been completely established and, consequently, the mechanism whereby peroxide decomposition promotes hydrocarbon conversions cannot be established with any great degree of certainty, it is believed probable, for

example, that in general the energized peroxides decompose either by the formation of intermediate free radicals, such as hydroxyl, alkyl, alkyl oxo, etc., or primarily to form nascent oxygen, depending on the temperature. These activated fragments and molecules enter reactions to form activated products which release their energy in various reactions and collisions to activate other molecules. The chain reactions initiated in this way involve activation and deactivation by intermolecular transfer of energy and, because of the increased formation of chain carriers, the overall rate of hydrocarbon conversion is increased. Peroxides acquire a degree of activation not shared by the entire system, and encourage rapid initiation of reaction chains.

Whatever the exact mechanism may be, in general peroxides will decompose rapidly and exothermally when suddenly heated, as for example, when injected into a reactor held at cracking temperatures, and the net effect of their presence upon hydrocarbon cracking reactions is to facilitate scission of carbon to carbon bonds and produce an increased reaction velocity. It is recognized that many types of peroxides are dangerous to handle and that many are too unstable and unpredictable to be of practical value. For example, it is known that the following peroxides explode upon heating or shock: cyclo-triacetone peroxide, diacetyl peroxide, diethyl peroxide, dimethyl fulvene peroxide, ethyl hydrogen peroxide, fumaryl peroxide, hexamethylene triperoxy diamine, methyl ethyl ketone peroxide, phthalyl peroxide, succinic peroxide and succinyl peroxide.

Many peroxides under ordinary conditions, however, are quite stable, and are found within the general class of hydroperoxides, ROOH, as well as within the general class of peroxides, ROOR, where R represents any hydrocarbon radical or substituted hydrocarbon radical. Thus, classes of compounds such as hydrocarbon hydroperoxides, hydrocarbon peroxides, the hydroperoxides and peroxides of hydroxy derivatives of hydrocarbons, acyl peroxides, peresters, and peracids can be included. Hydrocarbon peroxides and hydroperoxides constitute preferred classes for the purposes of this invention. Within this class, because of generally greater stability under the ordinary conditions of thermal change and shock involved in application and handling, hydrocarbon radicals containing at least four carbon atoms and a condensed structure, i. e., highly branched or cyclic compounds, are preferred. To some extent the same preference is

3

applicable to substituted hydrocarbon radicals. However, with the substituted radicals, the number of exceptions is somewhat greater because of the unpredictable influence of substituents. Of the classes of peroxidic compounds other than hydrocarbon peroxides and hydroperoxides, the α -hydroxyhydrocarbon hydroperoxides and peroxides, α,α' -dihydroxyhydrocarbon peroxides, and peresters are considered to be especially advantageous for the purposes of this invention. Specific examples of useful peroxides of the foregoing classes are as follows: di-tertiary-alkyl peroxides, such as di-tertiary-butyl peroxide, di-t-amyl peroxide, di-t-octyl peroxide, t-butyl pentamethyl-ethyl peroxide, di-triethylmethyl peroxide, di-t-dodecyl peroxide, etc., tertiary-alkyl hydroperoxides such as tertiary-butyl hydroperoxide, t-amyl hydroperoxide, t-octyl hydroperoxide, t-dodecyl hydroperoxide, etc., di-n-propyl peroxide, isopropyl hydroperoxide, di-sec-butyl peroxide, n-hexyl hydroperoxide, naphthene and unsaturated naphthene hydroperoxides and peroxides such as 1-methylcyclohexyl-1 hydroperoxide, t-butyl 1-methylcyclohexyl-1 peroxide, 1-methyl-3-methylene cyclopentyl-2 hydroperoxide, 2,3-dimethyl cyclopentyl-3 hydroperoxide, methyl cyclopentyl-6 peroxide, methyl 1-isopropyl-4-methylcyclohexenyl-3 peroxide, indan hydroperoxide, methyl indan peroxide, etc., terpene peroxides such as ascaridole, limonene 30 naphthalene peroxides and hydroperoxides such as tetralin hydroperoxide, methyl tetralin peroxide, etc., aromatic peroxides such as 1-phenylethyl-1 hydroperoxide, p-tolylmethyl hydroperoxide, etc., α -hydroxyhydrocarbon hydroperoxides and peroxides and α,α' -dihydroxyhydrocarbon peroxides such as α -hydroxyheptyl hydroperoxide, α -hydroxydodecyl hydroperoxide, α -hydroxynonyl hydroperoxide, hydroxy dicarbethoxymethyl hydroperoxide, α -hydroxyethyl methyl peroxide, α -hydroxymethyl ethyl peroxide, α -hydroxyethyl ethyl peroxide, α -hydroxyheptyl ethyl peroxide, α,α' -dihydroxydipropyl peroxide, α,α' -dihydroxydiethyl peroxide, α,α' -dihydroxydidecyl peroxide, α,α' -dihydroxydidecyl peroxide, α,α' -dihydroxydiisoamyl peroxide, di-(hydroxy-dicarbethoxymethyl) peroxide, etc., peresters such as t-butyl perbenzoate, t-butyl perstearate, t-butyl perundecylate, t-butyl diperadipate, t-butyl diperphthalate, t-amyl perbenzoate, dimethyl, diethyl, and diisopropyl perterephthalates, s-methyl perester-t-methyl camphorate, trans-9-decalyl perbenzoate, etc., acyl peroxides such as dibenzoyl peroxide, diphthalyl peroxide, dicamphoryl peroxide, etc., peracids such as d-camphoric acid peracid, diperoxic acid, diperbenzoic acid, diperphthalic acid, etc., and various other peroxides, for example peroxides of dioximes and derivatives thereof.

Of the foregoing examples of peroxides, most are relatively easy to prepare and quite safe to handle. Typical among these are tertiary-alkyl peroxides and hydroperoxides, hydroperoxides and peroxides of monocyclic saturated hydrocarbons having five or six carbon atoms in the ring, α -hydroxyalkyl hydroperoxides and peroxides α,α' -dihydroxydialkyl peroxides, terpene hydroperoxides and peroxides, tertiary-alkyl peresters, peroxides of the camphoric acid series, and monocyclic aryl acyl peroxides. Ascaridole, a terpene peroxide, is naturally available in crude form as American wormseed oil. One or more of the peroxides can be added to a hydrocarbon charge by either of the methods suggested above,

so that it will be present in the reaction zone where temperature conditions will induce its decomposition, thereby to accelerate the cracking or conversion of the hydrocarbon charge.

In a few instances, peroxides can be formed by the use of ozone, as, for example, in the preparation of terpene peroxides. Ramage (United States Patent 1,585,602, dated May 18, 1946), produced terpene peroxide, $C_{10}H_{18}O_2$, by blowing ozonized air through eucalyptus oil at 80° C. After removing the peroxide by a current of air, it was further oxidized to the diperoxide, $C_{10}H_{18}O_4$, with an excess of ozonized air. The diperoxide is a colorless oil which, when placed in contact with water, liberates active oxygen for a long period of time. Another method for producing terpene peroxides is to contact pinene, turpentine oil and other terpene containing hydrocarbon oils at 80° C. with oxygen in the presence of a heavy metal, such as cobalt, iron, lead, chromium, nickel resinate as catalyst.

Where a stable peroxide, safe to handle, cannot be readily prepared and isolated, the formation in situ and immediate use thereof are indicated. In accordance with these principles, those peroxides most easily and efficiently used would be the hydrocarbon peroxides, including those of olefins or diolefins. It is well known that diolefins form peroxides by reaction with oxygen much more readily than olefins. Thus, one practical embodiment of the process using certain safe, relatively stable peroxides as promoters of hydrocarbon cracking reactions would involve the following steps:

Hydrocarbon vapors to be cracked are passed with oxygen or air through a furnace at the relatively low temperatures of about 50° to about 400° C., or temperatures approaching the lowest temperatures at which cracking of the hydrocarbon to be processed will occur, to produce a maximum concentration of peroxides. Irradiation with ultraviolet light and metallic catalysts may be employed to increase the yield of peroxides. From this low temperature furnace, the vapors containing peroxides pass into a higher temperature cracking furnace. This procedure involving preliminary formation of peroxides accomplishes two purposes. First, peroxides are formed in the hydrocarbon to be cracked, and, second, the charge becomes preheated. If desired, naphthenes, unsaturates, highly cracked naphthas, terpenes, naphthalenes, or aromatics, can be added to a charge to facilitate formation of an adequate peroxide concentration therein. Hexane, cyclohexane and cyclohexene absorb oxygen very readily when heated and the formation of peroxides therein reaches a maximum at 330°, 340° and 410°, respectively (Estradere, Compt. rend., 1933, 196, 674). Tetralin is easily converted to the peroxide by air at temperatures under 100° C., even without a catalyst or irradiation (Hartmann and Seiberth, United States Patent 1,924,786, dated August 29, 1933).

The cracking of the hydrocarbons in the presence of peroxides may be carried out under sub-atmospheric, atmospheric or superatmospheric pressures at temperatures in ranges from the lowest at which any cracking will occur, to temperatures of approximately 2000° F. The lowest temperature at which cracking will occur is determined by the composition of the hydrocarbon oil and the objective of the hydrocarbon cracking or conversion, together with the amount and kind of the particular peroxide used to accelerate the reaction, for the thermal cracking threshold

temperatures for various hydrocarbons are known. When the cracking of a hydrocarbon oil to lower boiling liquids, such as gasoline, is carried out, temperatures ranging from approximately 650° to 1200° F. may be used. If the cracking of hydrocarbon oils or gases is for the purpose of producing aromatic hydrocarbons, temperatures of approximately 1000° to 1500° F. may be used. When it is desired to produce butane hydrocarbon oils, temperatures in the range of 1300° to 1600° F. give the best yields. Hydrocarbon oils are best cracked to gaseous hydrocarbons at temperatures from approximately 1300° to 3000° F.

For the injection of the peroxide into the reaction zone, conventional types of thermal cracking apparatus, as well as catalytic cracking apparatus, can be used without any necessity of changing the fundamental operation of the process or redesigning the apparatus, except to make adequate provision for charging the peroxide in the correct amount. Preferably, the amount of peroxide in the reaction zone should be kept in the range from 0.05 to about 3 mol per cent. In this connection, the peroxide is preferably introduced at successive points in aliquot parts through the reaction zone.

For example, in the practice of the invention, gas-oil is charged to a preheating coil in a thermal cracking operation conducted at a maximum temperature of approximately 900° F., and at a pressure of approximately 500 pounds per square inch. In the preheating coil, the charge is heated to a temperature of approximately 700° F., and passes into the cracking coil into which a solution of a peroxide in a portion of the gas-oil is injected in such amount that the mol ratio of the peroxide to gas-oil undergoing cracking is about 0.001. The yield of gasoline obtained is considerably in excess of that obtained in a similar operation without using any cracking sensitizer.

As a specific modification of the process outlined, a solution of di-t-butyl peroxide in benzene is injected into a reactor, in which gas-oil is undergoing cracking at a temperature of approximately 850° F., in an amount such that the mol ratio of t-butyl peroxide to gas-oil is approximately 0.01. The resultant yield of gasoline is as good as can be obtained at higher temperatures without sensitizers.

Although the specific examples involve cracking of gas-oil, it is to be understood that the invention is applicable to cracking of methane to acetylene, cracking of propane and butanes to ethylene and propylene, and cracking of hydrocarbon oils in general to lower boiling hydrocarbons, as well as to other hydrocarbon conversions, such as polyforming, isomerization, alkylation, dehydrocyclization, hydroforming, and reforming.

It will be seen, therefore, that I have succeeded in providing a way for improving hydrocarbon cracking or conversion processes in that by adding a small amount of peroxide to the hydrocarbon undergoing cracking, reforming, or other conversion, yields of desirable products can be materially increased for any particular set of reaction conditions, or the reaction can be carried out at lower temperatures and/or in less time without suffering any decrease in yield of desirable products.

What is claimed is:

1. The process of cracking hydrocarbon oil to lower-boiling liquid motor fuel hydrocarbons which consists in subjecting said hydrocarbon oil to cracking conditions of time, temperature

and pressure in the presence of a small amount of an organic peroxide stable against explosive decomposition under shock and at ambient temperatures, said peroxide being present in amount sufficient to induce a material increase in the rate of cracking.

2. The process of cracking hydrocarbon oils to hydrocarbons substantially within the gasoline boiling range, which consists in subjecting the said oils to temperatures of approximately 650° to 1200° F., in a cracking zone in the presence of approximately 0.05 to 3 mol per cent of a non-explosive organic peroxide, the amount of said peroxide being sufficient to induce a material increase in the rate of cracking.

3. The process of cracking hydrocarbon oils to hydrocarbons substantially within the gasoline boiling range which consists in subjecting the said oils to temperatures of approximately 650° to 1200° F. in a cracking zone in the presence of approximately 0.05 to 3 mol per cent of an organic peroxide, stable against explosive decomposition under shock and at ambient temperatures, the amount of said peroxide being sufficient to induce a material increase in the rate of cracking.

4. The method in accordance with claim 3 in which the peroxide is a hydroperoxide.

5. The method in accordance with claim 2 in which the peroxide is a peroxide of a hydrocarbon.

6. The method in accordance with claim 2 in which the peroxide is an alkyl peroxide.

7. The method in accordance with claim 2 in which the peroxide is an alkyl peroxide with at least four carbon atoms in the alkyl radical.

8. The method in accordance with claim 2 in which the peroxide is a tertiary-alkyl peroxide.

9. The method in accordance with claim 2 in which the peroxide is a naphthene peroxide.

10. The method in accordance with claim 2 in which the peroxide is a peroxide of a monocyclic naphthene with a ring of 5 to 6 carbon atoms.

11. The method in accordance with claim 2 in which the peroxide is a terpene peroxide.

12. The method in accordance with claim 2 in which the peroxide is an aromatic peroxide.

13. The method in accordance with claim 2 in which the peroxide is a naphthalene peroxide.

14. The method in accordance with claim 2 in which the peroxide is an alkylene peroxide.

15. The method in accordance with claim 2 in which the peroxide is an alkylene peroxide with at least four carbon atoms in the alkylene radical.

16. The method in accordance with claim 2 in which the peroxide is a perester.

17. The method in accordance with claim 2 in which the peroxide is a tertiary-alkyl perester of a carboxylic acid, the radical of which carboxylic acid contains at least four carbon atoms.

18. The method in accordance with claim 2 in which the peroxide is a peracid.

19. The method of cracking hydrocarbon oil to lower-boiling liquid motor fuel hydrocarbons which consists in continuously passing a stream of the hydrocarbon oil to be cracked to reaction zone, where it is maintained under cracking conditions of time, temperature and pressure and concurrently subjecting a peroxide-forming material in a separate zone to peroxidation conditions to generate a peroxide in situ which is thermally and shock stable at ordinary temperatures but which decomposes rapidly under cracking conditions, injecting an aliquot portion of 75 said peroxide solution into the reaction zone con-

taining the hydrocarbon in amount sufficient to create a reaction mixture containing sufficient peroxide to induce a material increase in the rate of cracking, and recovering from the reaction zone cracked lower-boiling hydrocarbons.

20. The method in accordance with claim 19 in which the peroxide-forming material is a hydrocarbon.

21. The method in accordance with claim 19 in which the peroxide-forming material is an olefin having at least four carbon atoms.

22. The method in accordance with claim 19 in which the peroxide-forming material is a naphthene.

23. The method in accordance with claim 19 in 15

which the peroxide-forming material is a terpene.
